ROLLER BLIND AND FITTINGS THEREFOR

Filed July 2, 1927

II. Inventor: William James Fadden
By John J. S. Attorney

UNITED STATES PATENT OFFICE

WILLIAM JAMES HADDEN, OF GLASGOW, SCOTLAND, ASSIGNOR TO DONALDSON MANUFACTURING COMPANY LIMITED, OF GLASGOW, SCOTLAND

ROLLER BLIND AND FITTINGS THEREFOR

Application filed July 2, 1927, Serial No. 203,145, and in Great Britain June 10, 1927.

This invention relates to roller blinds of the type including means (such, for instance, as a ratchet wheel) held to the blind roller by friction for permitting the blind to be lowered to and held in different positions while said means is held stationary, and refers also to the fittings for said roller blinds.

The object of the present invention is to provide a roller blind, (particularly adapted for rail cars and carriages and private and public road vehicles) which is capable of being operated from either end at will by two cords provided for this purpose, the roller of the blind preferably being so arranged that the cord operated is retracted at the end of each operation, so as to occupy a fixed position, irrespective of the position of the blind, whereby, in the vehicles aforesaid, the blind cords and their tassels will not freely swing about, the tassels normally being held up against the roller or its fitting.

According to the present invention, the roller blind is provided at both ends of the roller with means for raising the blind, means for normally holding said raising means stationary and means for holding said raising means to the roller by friction for permitting the blind to be lowered to and held in different positions while the raising means is held stationary.

To retract the cord operated, the raising means is arranged so that it can be rotated in one direction independently of the roller, means being provided for automatically returning said raising means and its cord to its initial position after the blind has been moved to a required position. In this case the cord may act normally to hold the raising means stationary.

40 Referring to the drawings:—

Fig. 1 is a side elevation of a window with the blind applied thereto.

Fig. 2 is a longitudinal sectional elevation through the blind roller.

45 Fig. 3 is a sectional view on line III—III in Fig. 2 looking in the direction of the arrow.

Fig. 4 is a sectional view on line IV—IV in Fig. 2 looking in the direction of the arrow.

Fig. 5 is a longitudinal sectional view of one of the end fittings removed and drawn to an enlarged scale.

Fig. 6 is a section on line VI—VI in Fig. 5.

In the practical embodiment shown in the drawings the roller 1 and blind 2 may be of any usual form. The end members are constructed as separate fittings each of which comprises a circular flanged disc 5 engaging and fixed by screws 4 to the proximate end of the roller and an axially extending journal 3 which is formed with a shoulder 6 between its end and the disc and is screwed at its end 7. On this journal there is a loosely mounted ratchet wheel 13 which is frictionally clutched to the journal by a spring washer 11 located between the shoulder 6 and a disc washer 12 in contact with the ratchet wheel 13. A cord drum is located on the journal at the outer side of the ratchet wheel, in contact with the side thereof, this drum being rotatably mounted on a sleeve nut 15 screwed upon the journal and being provided with two oppositely extending cylindrical flanges 16, 17 within which there is fitted disc rings 18, 19, the one 19 at the outer end being removable. Between the drum and the inner disc ring 18 there is mounted a number of, say three, pawls 20 rockable on rivets 21 extending between the said drum flange and disc ring, and adapted to engage with the ratchet wheel. Within the outer flanged part 17 and rotatably mounted on the sleeve-nut 15 is a sleeve 22 between which and the said flanged part is located a coil spring 23 anchored to the two parts. One end 24 of the spring 23 is passed through slots 25 in the flanged part 17 and the other end 26 is passed through a slot 27 in the sleeve 22. This end fitting is also enclosed in a two part cover 30, 31, one part 30 having projections 32 which engage in slots 33 in the sleeve and having a bearing spindle 34 which projects within the sleeve nut 15. The cord 35 which is adapted to wind around the part between the drum flanges, is secured at one end by passing it through a hole 37 in one flange and knotting this end of the cord. The other end of the cord passes through a hole 38 in the cover part 30 and is preferably

provided with a tassel 39 or other similar device.

The two part covers 30, 31 are made to fit detachably together so that the end fitting can be inspected and parts thereof adjusted, removed, changed and replaced. These covers are provided with apertured lugs 40 by which they can be fixed to the window frame 41.

10 The sleeve nut 15 can be moved by screwing it more or less on to the journal and by this means the tension of the spring washers can be adjusted. A grub screw 47 is provided in the sleeve-nut, which when screwed

15 against the journal serves to lock the sleeve-nut in its adjusted position. By removing the covers, the sleeve-nuts and other parts can be readily adjusted, removed and changed or replaced.

20 The window frame 41 is preferably provided with two guide ropes 50 adapted to engage in eyed projections 51 fixed to the usual blind stick 52, said ropes being attached to the window frame by eyed projections 53. The blind is provided with a tassel 54.

The two end members are of identical construction except that, the journal, sleeve-nut and grub screw at the right hand end are provided with left hand threads and the same parts at the left hand end are provided with right hand threads to prevent these parts from unscrewing by the operation of the blind.

25 Assuming the parts constituting the roller blind have been assembled and fixed in place and assuming that the blind is up and that each cord has been wound around its drum so that only the tassel 39 extends beyond the end casing, then in operation, when the blind is pulled down the roller is rotated, the ratchet wheels being retained by their pawls so that the ratchet wheels are stationary, the roller rotating against the friction set up by the spring washers. The blind will stay in any

30 position to which it is moved. To raise the blind either of the tassels 39 is pulled causing the cord 35 to rotate the drum and through the pawls thereon rotating the ratchet wheel

35 which, in turn, rotates the roller, the friction set up between the parts by the spring washer 11 preventing relative movement of the parts.

In this rising movement the ratchet wheel of the opposite end fitting to that whose cord is operated runs free. Moreover, in this rising

40 movement the coil spring 23 of the cord drum which is rotated will be tightened by the rotation of the drum relative to the sleeve. When, therefore, the blind has been moved up to the required position and the tassel released the drum will be rotated by the coil spring so as to return the drum to its initial position relative to the casing, automatically rewinding the cord on to the drum and thereby re-

45 tracting it to its original position. The tassel

39 will cooperate with the cover part 30 normally to hold the cord drum stationary.

In this way the blind can be raised from either end, when and to the extent required and the cord will be rewound or retracted to its initial position irrespective of the position of the blind.

It will be understood that it is not essential that the cord be, as assumed, entirely rewound or retracted, the important point being that 75 the cord is rewound or retracted to its original position so that a minimum and constant amount of cord is hanging irrespective of the position of the blind.

I claim:

1. A roller blind having at each end of said roller a fitting comprising, a journal having a screwed end, a ratchet wheel rotatably mounted on each journal, means for frictionally holding said ratchet wheel to 85 the journal to allow the blind to be lowered and held in different positions while the ratchet wheel is stationary, a sleeve nut screwing on said journal and engaging the ratchet wheel and serving to vary the friction holding 90 said ratchet wheel to the journal, a screw for locking said sleeve nut in its adjusted position, a cord drum rotatably mounted on said sleeve nut, a cord on said drum adapted to rotate it, pawls on said drum engaging said ratchet 95 wheel, adapted when the drum is rotated by the cord to rotate the roller but to allow the drum to rotate in the opposite direction independently of said roller, supporting means adapted to be fixed to window frame and 100 engaging in the sleeve nut, a coil spring fixed at one end to said cord drum and adapted automatically to return the cord drum to its initial position after the blind has been moved to a required position by a pull on said cord 105 whereby the cord is retracted, anchoring means on said sleeve nut for the other end of said coil spring, means on said supporting means to engage detachably with and hold said anchoring means stationary and means 110 for normally holding said cord drum stationary whereby the blind can be raised by pulling the cord at either end of the roller, downward movement of the blind being checked at one end while raising means at 115 the other end is being operated.

2. A roller blind operating mechanism embodying a roller upon and from which the blind is adapted to be wound, normally inactive actuating means at each end of the roller for rotating the roller in a direction to wind the blind thereupon, said roller being rotatable independently of both of said actuating means as the blind is unwound, means individual to the said actuating means for selectively rendering them active for operating the roller from either end to wind the blind upon the roller, each of said blind raising means operating to maintain the blind against downward movement when the other of the 125

said raising means is actuated, and means independent of said actuating means for maintaining the blind in any desired position.

3. A roller blind operating mechanism embodying a roller upon and from which the blind is adapted to be wound, normally inactive actuating means at each end of the roller for rotating the roller in a direction to wind the blind thereupon, said roller being rotatable independently of both of said actuating means as the blind is unwound, means individual to the said actuating means for selectively rendering them active for operating the roller from either end to wind the blind upon the roller, each of the last said means embodying a drum, a pull cord wound thereupon and adapted to be unwound therefrom to rotate the drum, each of said blind raising means operating to maintain the blind against downward movement when the other of the blind raising means is actuated, and means individual to the drums and rendered active by the unwinding action of said pull cords, for rotating the respective drums in the opposite direction independent of said roller to rewind the respective pull cords upon the respective drums.

4. A roller blind having in combination, a roller, a blind thereon, two devices one at each end of the roller, each device comprising unidirectional clutching means, both clutching means being adapted to act on the roller in the same rotative sense, and means in connection with each said device for raising the blind, both of the said devices co-operating with the roller to hold the blind in position when lowered but one of the devices operating and the other remaining inactive when the blind is raised by one of the blind raising means.

5. A roller blind having in combination, a roller, a blind thereon, two devices one at each end of the roller, each device comprising unidirectional clutching means, both clutching means being adapted to act on the roller in the same rotative sense, and means in connection with each said device for raising the blind, both of the said devices co-operating with the roller to hold the blind in position when lowered, and both devices operating to raise the blind when the blind is being raised by both blind raising means.

6. A roller blind having in combination, a roller, a blind thereon, two devices one at each end of the roller, each device comprising unidirectional clutching means, spring means and frictional contact means, both clutching means being adapted to act on the roller in the same rotative sense, and means in connection with each said device for raising the blind, both of the said devices co-operating with the roller to hold the blind in position when lowered but one of the devices operating and the other remaining inactive when the blind is raised by one of the

blind raising means, one of the spring means acting to retract the blind raising means after the blind has been raised.

7. A roller blind having in combination, a roller, a blind thereon, two devices, one at each end of the roller, each device comprising unidirectional clutching means, spring means and frictional contact means, both clutching means being adapted to act on the roller in the same rotative sense, and means in connection with each said device for raising the blind, both of the said devices co-operating with the roller to hold the blind in position when lowered, and both devices operating to raise the blind when the blind is being raised by both blind raising means, both of the spring means acting to retract the blind raising means after the blind has been raised.

8. A roller blind having in combination, a roller, a blind thereon, two devices one at each end of the roller, each device comprising unidirectional clutching means, spring means and frictional contact means, both clutching means being adapted to act on the roller in the same rotative sense, a cord and a drum therefor in connection with each said device for raising the blind, both of said devices co-operating with the roller to hold the blind in position when lowered, but one of the devices operating and the other remaining inactive when the blind is raised by one of the cords.

9. For a roller blind, the combination of a roller, roller turning means at each end of said roller adapted to turn said roller in the blind raising sense, unidirectional clutching means between each end of the roller and the corresponding roller turning means, friction clutching means between each end of the roller and the corresponding unidirectional clutching means and resilient means at each end of said roller and adapted to be stressed by blind raising movement of the corresponding roller turning means, either of the resilient means acting to return the corresponding roller turning means to its normal position after the blind has been raised thereby and the unidirectional clutching means at the other end of the roller simultaneously coacting to prevent turning of the roller in the blind lowering sense.

10. A roller blind having in combination, a roller, a blind thereon, two devices one at each end of the roller, each device comprising unidirectional clutching means, both clutching means being adapted to act on the roller in the same rotative sense, and means in connection with each said device for raising the blind, the two said devices co-operating, one to retract the blind raising means after the blind has been raised and the other simultaneously to prevent such retraction causing movement of the roller in the blind lowering sense.

11. A roller blind having in combination, a roller, a blind thereon, two devices one at each

end of the roller, each device comprising unidirectional clutching means, spring means and frictional contact means, both clutching means being adapted to act on the roller in the same rotative sense, and means in connection with each said device for raising the blind, the two said devices co-operating, one to retract the blind raising means after the blind has been raised and the other simultaneously to prevent such retraction causing movement of the roller in the blind lowering sense.

In testimony whereof I affix my signature.
WILLIAM JAMES HADDEN.
